UNITED STATES PATENT OFFICE.

HENRY F. SHAW, OF WEST ROXBURY, ASSIGNOR TO JAMES A. WOODBURY,
OF BOSTON, MASSACHUSETTS.

IMPROVEMENT IN CUTTING APPARATUS FOR MOWING-MACHINES.

Specification forming part of Letters Patent No. **104,364**, dated June 14, 1870.

To all whom it may concern:

I, HENRY F. SHAW, of West Roxbury, in the county of Norfolk and State of Massachusetts, have invented certain new and useful Improvements in Mowing-Machines, of which the following is a specification:

The Nature and Object of the Invention.

The nature of my invention consists in a new and peculiar device for operating the cutter-bar of a mowing-machine, the device being to operate the cutter-bar by means of two pitmen, which are attached to two cranks set diametrically opposite each other, one of the pitmen acting directly upon the cutter-bar in the usual manner, while the other one, always moving in an opposite direction, acts in combination with a cutter-balance or slide upon the cutter-bar through an intervening lever, the object of the invention being to concentrate the effect of the action and reaction due to the motion and work of the cutter-bar upon the same point—that is, upon the driving-shaft—and to balance the same, so that the body of the machine shall be freed from vibration.

Description of the Accompanying Drawings.

Figure 1 is a perspective view illustrating my invention. Fig. 2 is a plan of the same.

General Description.

B represents the driving-shaft, which is provided with two cranks, D and D', these cranks being set diametrically opposite to each other, and serve to operate the two pitmen H and E.

The pitman H acts directly on the cutter-bar K in the usual manner, while the pitman E, always moving in the opposite direction, acts through the counter-balance slide P and the lever L, the lever L having its fulcrum at M.

By this arrangement of uniting two pitmen which operate in different directions any strain on the cutter-bar will be divided, so that one half of it will act upon the driving-shaft in one direction, while the other half will act upon the driving-shaft in the opposite direction, while the effect due to momentum of the cutter-bar will be balanced by the balance-slide P, so that any strain, either of momentum or work, will exactly counterbalance itself on the driving-shaft.

I claim as my invention—

The combination of the double crank D D', the pitmen H and E, the lever L, and balance P with the cutter-bar K, operating as described, and for the purpose set forth.

Witnesses: HENRY F. SHAW.

FRANK G. PARKER,
A. HUN BERRY.
